UNITED STATES PATENT OFFICE.

PAUL L. WOSS, OF CHICAGO, ILLINOIS.

VENEER-GLUING PRESS.

1,188,525.

Specification of Letters Patent. Patented June 27, 1916.

Application filed July 1, 1915. Serial No. 37,477.

To all whom it may concern:

Be it known that I, PAUL L. Woss, a citizen of the United States, and a resident of the city of Chicago, county of Cook, and 5 State of Illinois, have invented certain new and useful Improvements in Veneer-Gluing Presses, of which the following is a specification.

My invention relates to improvements in 10 veneer gluing presses, and has for its object the production of a device of this character which will be of durable and economical construction and efficient in use.

Other objects will appear hereinafter.

15 The invention consists in the combinations and arrangements of parts hereinafter described and claimed.

The invention will be best understood by reference to the accompanying drawings 20 forming a part of this specification, and in which,

Figure 1 is a perspective view of a veneer gluing press embodying the invention, Fig. 2 is a partially sectional side elevation of 25 the press, Fig. 3 is an elevation of one end of the clamping device of the press, with a plate removed to expose underlying parts and portions shown in section, Fig. 4 is an elevation of the opposite end of the 30 clamping device, Fig. 5 is an enlarged section taken on substantially line $x-x$ of Fig. 4, Fig. 6 is a fragmentary perspective view of one of the clamping jaws included in the invention, and Fig. 7 is a detail section 35 taken on substantially line $y-y$ of Fig. 5.

The preferred form of construction, as 40 illustrated in the drawings, comprises a bed or table 1 which is supported upon legs 2. Arranged in opposite parallel edges of the bed 1 are channel guides or rails 3 which are rigidly secured in position.

Coöperating with the bed 1 is a clamping device consisting of a carriage which 45 comprises end members 4 and 5 which are positioned at the opposite edges of said bed, and which are rigidly connected by a connecting member 6 which extends under the bed, as clearly shown in Fig. 5. Provided upon the inner sides of end members 50 4 and 5 are rollers 7 which engage in the channels 3 to loosely support the carriage, it being clear that with this arrangement, the

carriage and hence the clamping device is free for adjustment along the bed to any position desired.

Coöperating with the upper side of the bed 1 is a plurality of clamping arms 8 each of which comprises an elongated body 9 which is hinged at one end as at 10, to the end member 4 of the carriage.

Coöperating with each clamping arm is a leaf spring 11 which serves to normally hold the free end of the former in elevated or inoperative position, one end of said spring being secured to the end member 4, 65 the opposite end thereof pressing against the under side of the adjacent downwardly projecting end of the body 9. Also coöperating with each clamping arm is a counter-balance weight 12 the purpose of which 70 is to assist the spring 11 in normally holding the clamping arm in inoperative position. Each weight 12 is connected with the corresponding clamping arm by means of a shank 13 which is fastened to the rearward 75 end of the arm by means of a thumb nut 14 and a coöperating threaded stud 15, said stud projecting upwardly from the clamping arm through an elongated slot 16 formed in the shank, as clearly shown in 80 Figs. 1 and 5. With the construction set forth, it will be seen that the counter-balance weight members are connected with the clamping arms in such a manner as to 85 permit of adjustment so as to secure the desired balancing effect upon the clamping arms.

The clamping arm bodies 9 are locked in lowered or operative position by means of pawls 17 pivoted at 18 in the end member 90 5, said pawls being adapted for engagement with depending loops or staples 19 provided at the outer ends of the members 9, as clearly shown in Fig. 3. A leaf spring 20 coöperates with each pawl 17 for normally holding the same in operative position, the arrangement being such that upon lowering of any arm member 9 to operative position, the same will be automatically locked in this position through engagement 95 of the corresponding pawl 17 with the corresponding loop or staple 19. The pawls 17 are simultaneously rocked to releasing position by means of an exteriorly projecting

handle 21 which is fulcrumed at 22 in the end member 5. The inner end of arm 21 is adapted to engage with one arm of a bell crank lever 23 which is pivoted at 24 in member 5, the other arm of said bell crank lever engaging with a plate 25 which is shiftably mounted upon headed pins 26 which engage with elongated slots 27 formed in said plate. In the upper edge of plate 25 are formed shoulders 28 which are adapted for engagement with the lower ends of pawls 17, the arrangement being such that, upon shifting of the plate 25 to the right, as shown in Fig. 3, said pawls will be rocked to releasing position. The handle 21 is operatively connected with the plate 25 through the medium of the bell crank lever 23 so that upon downward rocking of the outer end of said handle, said plate 25 will be shifted as mentioned to effect rocking of the pawls 17 to releasing position. Hence with this arrangement, unlocking of the clamping arm is effected by simply depressing the outer end of handle 21. Upon release of said handle, the springs 20 acting through the medium of pawls 17, will shift the plate 25 back to its initial position, as shown in Fig. 3.

Arranged at the under side of each of the arm members 9 is an elongated clamping jaw 29, the former being cut away as shown to accommodate said jaw. Arising from each jaw 29 are two pins 30 which slidably engage openings 31 formed in the corresponding member 9. The openings 31 are reinforced, as seen, with metallic bushings. With this arrangement the jaws 29 will be locked against longitudinal or horizontal movement but permitted free transverse or vertical movement. The under side of each jaw is inclosed in a reinforcing protecting channel 32 formed of sheet metal which is secured in position by bolts and coöperating nuts 33.

Provided upon the upper end of each jaw 29 is an elongated plate 34, the corresponding arm member 9 being slotted as at 35 to afford clearance for said plate. Each of the plates 34 is shiftably secured to the corresponding jaw by means of angular keepers 36 which engage with laterally projecting flanges 37 provided at the lower edge of said plate, as clearly shown in Fig. 6. Formed in each of the plates 34 is a pair 38 of inclined cam slots which are engaged by transversely extending pins 39 secured to the corresponding arm body 9. With this arrangement, it will be seen that vertical movement of any one of the clamping jaws 29 may be effected by simply shifting the cam plate 34 coöperating therewith, it being clear that upon shifting of said plate, the pins 39 will engage with the longitudinal edges of the slots 38 coöperating with said jaw and thus effect raising or lowering of

the jaw, depending upon the direction in which the plate is moved. Shifting of each plate 34 is effected by means of a lever 40 which is fulcrumed at 41 to each of the arm members 9, the lower end of said lever 70 being provided with an elongated slot 42 which engages with a laterally projecting pin 43 provided upon the corresponding plate 34. With this arrangement, it will be seen that shifting of any one of the plates 75 34 may be effected by simply tilting the corresponding lever 40.

In using the press, the veneer and the work to which the same is to be applied are arranged upon the bed 1. After the veneer 80 has been placed as desired upon the work, the clamping arms 8 are rocked downwardly to operative position, the same being automatically locked in this position by means of the pawls 17, as above described. 85 When this is done, the clamping jaws 29 are pressed into secure engagement with the veneer through tilting of the levers 40, said jaws being locked in clamping position through frictional engagement of the plates 90 34 with the pins 39. In releasing the clamping arms, the levers 40 are first rocked to raise the jaws 29, whereupon the handle 21 is depressed to unlock the outer ends of said arms. This having been done, the springs 95 11 and counter-balance weights 12 serve to automatically rock the clamping arms upwardly to inoperative position.

While I have illustrated and described the preferred form of construction for carrying my invention into effect, this is capable of variation and modification without departing from the spirit of the invention. I, therefore, do not wish to be limited to the precise details of construction set forth, 105 but desire to avail myself of such variations and modifications as come within the scope of the appended claims.

Having described my invention what I claim as new and desire to secure by Letters 110 Patent is:

1. In a veneer gluing press, the combination of a bed; a plurality of clamping arms swingingly mounted above said bed for co-operation with the upper side thereof; means for locking said arms in operative relation with the bed; means for rocking said arms to inoperative position when released, said means comprising a spring; and an adjustable weight coöperating with each 115 arm arranged adjacent the pivot thereof, substantially as described.

2. In a veneer gluing press, the combination of a bed; a clamping arm swingingly mounted above said bed for co-operation 125 with the upper side thereof, said arm comprising a body; a jaw mounted at the under side of said body for relative movement toward and from the latter; means for relatively moving said jaw, said means compris- 130

- ing contact members on said body; a member shiftably connected with said jaw and having inclined cam surfaces engaging said contact members whereby said jaw will be moved upon shifting of said cam member; and means for shifting said cam member, substantially as described.
3. In a veneer gluing press, the combination of a bed; a clamping arm swingingly mounted above said bed for coöperation with the upper side thereof, said arm comprising a body; a jaw mounted at the under side of said body for relative movement toward and from the latter; means for relatively moving said jaw, said means comprising contact members on said body; a member shiftably connected with said jaw and having inclined cam surfaces engaging said contact surfaces whereby said jaw will be moved upon shifting of said member; and an exteriorly projecting lever for shifting said cam member, substantially as described.
4. In a veneer gluing press, the combination of a bed; a clamping arm swingingly mounted above said bed for coöperation with the upper side thereof, said arm comprising a body; a jaw mounted at the under side of said body for relative movement toward and from the latter; means for relatively moving said jaw, said means comprising contact members on said body; a member shiftably connected with said jaw and having inclined cam surfaces engaging said contact surfaces whereby said jaw will be moved upon shifting of said cam member; and an exteriorly projecting lever fulcrumed intermediate its ends to said body and having its inner end connecting said cam member whereby the latter will be shifted upon tilting of said lever, substantially as described.
5. In a veneer gluing press, the combination of a bed; a clamping arm mounted above said bed for coöperation with the upper side thereof, said arm comprising a body; a jaw mounted at the under side of said body for vertical movement relative thereto; means for vertically moving said jaw, said means comprising a plate arising from the upper side of said jaw and connected therewith, said plate having inclined slots formed therein; transversely extending pins in said body engaging said slots whereby said jaw will be vertically moved upon shifting of said plate; and means for shifting said plate, substantially as described.
6. In a veneer gluing press, the combination of a bed; a clamping arm mounted above said bed for coöperation with the upper side thereof, said arm comprising a body; a jaw mounted at the under side of said body for vertical movement relative thereto; means for vertically moving said jaw, said means comprising a plate arising from the upper side of said jaw and shift-
- ably connected therewith, said plate having a longitudinally extending slot provided at the under side of said body and having inclined elongated slots formed therein; transversely extending pins in said body engaging in said slots whereby said jaw will be vertically moved upon shifting of said plate; and means for shifting said plate, substantially as described.
7. In a veneer gluing press, the combination of a bed; a clamping arm mounted above said bed for coöperation with the upper side thereof, said arm comprising a body; a jaw mounted at the under side of said body for vertical movement relative thereto; means for vertically moving said jaw, said means comprising a plate arising from the upper side of said jaw and slidably connected therewith, said plate having inclined slots formed therein; transversely extending pins in said body engaging said slots whereby said jaw will be vertically moved upon shifting of said plate; and a pivoted lever having a slot and pin connection with said plate for shifting the same, substantially as described.
8. In a veneer gluing press, the combination of a bed; a clamping arm mounted above said bed for coöperation with the upper side thereof, said arm comprising a body; a jaw mounted at the upper side of said body for vertical movement relative thereto; pins arising from said jaw loosely engaging in openings provided in said body for holding said jaw against relative longitudinal movement; means for vertically moving said jaw, said means comprising a cam member arising from the upper side of said jaw and shiftably connected therewith, said cam member having inclined cam surfaces formed therein; transversely extending pins in said body engaging said cam surfaces whereby said jaw will be vertically moved upon shifting of said cam member; and means for shifting said cam member, substantially as described.
9. In a veneer gluing press, the combination of a bed; a clamping arm mounted above said bed for coöperation with the upper side thereof, said arm comprising a body; an elongated jaw mounted at the under side of said body; pins arising from said jaw loosely engaging in openings formed in said body for locking the same against longitudinal movement but permitting of free transverse movement; and manually operable cam mechanism for moving said jaw vertically, substantially as described.
10. In a veneer gluing press, the combination of a bed; a plurality of clamping arms swingingly mounted above said bed for coöperation with the upper side thereof; means operating with the free ends of said arms for locking the same in operative relation with said bed; and manually operable

means coöperating with said locking means for simultaneously actuating the latter to releasing position, substantially as described.

11. In a veneer gluing press, the combination of a bed; a plurality of clamping arms swingingly mounted above said bed for coöperation with the upper side thereof; a spring pressed pawl coöperating with each of said arms for locking the same in operative relation with said bed; and manually operable means coöperating with said pawls for simultaneously moving the same to releasing position, substantially as described.

12. In a veneer gluing press, the combination of a bed; a plurality of clamping arms swingingly mounted above said bed

for coöperation with the upper side thereof; a spring pressed pawl coöperating with each of said arms for locking the same in operative relation with said bed; and a pivotally mounted manually operable lever coöperating with said pawls for simultaneously moving the same to releasing position, substantially as described. 20

In testimony whereof I have signed my name to this specification in the presence of two subscribing witnesses. 5
